United States Patent Office.

THOMAS TRACY, OF NEW BRITAIN, CONNECTICUT.

Letters Patent No. 62,981, dated March 19, 1867.

IMPROVEMENT IN BUTT MACHINES.

The Schedule referred to in these Letters Patent and making part of the same.

TO ALL WHOM IT MAY CONCERN:

Be it known that I, THOMAS TRACY, of New Britain, county of Hartford, and State of Connecticut, have invented certain new and useful improvements in Machinery for Driving Wires into the Joints of Butts; and I do hereby declare that the same is described and represented in the following specification and drawings. And to enable others skilled in the art to make and use the same, I will proceed to describe its construction and operation, by referring to the drawings, in which the same letters indicate like parts in each of the figures.

This improvement relates only to that part of a butt machine which performs the work of holding, distributing, and driving the wire into the joints of butts, without reference to any particular mode or mechanism for applying the power for operating its parts; the nature of which consists in so constructing the mechanism for holding and driving the joint wire into the joint of a butt as to effectually prevent it or the driver from kinking. In the accompanying drawings—

Figure 1 is a top view.

Figure 2 is an end view of the device, which lies parallel with the end of a butt, in readiness to receive the joint wire.

Figure 3 shows a top and end view of the driver-bar.

a is a butt, placed or moving through a machine in the usual way, and resting at the point for receiving its centre pin or wire which completes the joint of the butt. *b* is the device or bed which lies parallel with the line of the end of the butt *a*, in and near the centre of which is arranged a sliding driver-bar, *c*, so as to move in a straight line with the centre of the butt, on the upper edge and near the centre of which is formed a driver, *d*, of about three equal sides, and equal to the diameter of the wire of the butt. This bar or driver *d* is operated in the usual way of operating the punch or driver usually employed for driving the wire into the joint of butts. On one side of this driver-bar *c*, and at the forward end, is made a wedge formation, *e*, and a button, *f*, of about the same thickness of the driver-bar *c*, below the edge of the driver *d*, having its edge *g* curved for the wedge formation of the driver-bar *c* to work against, so that as the driver moves forward the button recedes, and as the driver moves back the button is reacted by a spring, *h*. The object of this button *f* is to form a bed for the wires to rest upon. *i* is a slide or cut-off, arranged so as to move back and forth in the bed, closely over the top edge of the driver *d*, and having its cut-off edge bevelled, so that its edge will slide between the wires and separate one from the others, to be driven forward into the butt-joint. *k* are wires placed in a receiver, the lower end of which is open directly at the end of the cut-off, so that the cut-off regulates their movements, and only one be discharged from the receiver at a time.

Now it will be seen that when the machine is set in motion the wires *k* will fall down between the sides of the bed-plate upon the button, the cut-off moves forward over the upper side of one wire. Thus it (the wire) is closely encased on four sides, when the driver-bar *c* moves forward, forcing the wire in a straight line into the joint of the butt without the least liability of crooking or kinking.

I believe I have thus shown the nature, construction, and operation so as to enable a person skilled to make and use the same therefrom.

What I claim, therefore, and desire to secure by Letters Patent, is—

I claim the spring button *f*, and tongued bar *c*, or their equivalents, in combination with suitable mechanism for operating said bar, substantially in the manner and for the purpose as described.

THOS. TRACY.
